UNITED STATES PATENT OFFICE.

EDWIN E. BARNEY, OF NEW ROCHELLE, NEW YORK, ASSIGNOR TO REMINGTON TYPE-WRITER COMPANY, OF ILLION, NEW YORK, A CORPORATION OF NEW YORK.

TYPEWRITING MACHINE.

Application filed December 8, 1927. Serial No. 237,485.

My invention relates to typewriting and similar machines and it has for its principal object to provide an elastic stop for arresting the carriage, especially when said carriage is drawn back to the right.

My invention consists in an elastic stop device of novel construction and the combination and relative arrangement therewith of other devices.

10 One form of my invention is illustrated in the accompanying drawings in which

Fig. 1 is a fragmentary front elevation of the upper part of a typewriter with my invention applied thereto.

15 Fig. 2 is a similar view of a portion of the same but with certain parts removed.

Fig. 3 is a view in section on the line 3—3 of Fig. 1 and looking in the direction of the arrow.

20 Fig. 4 is a section taken partly on the line 4—4 of Fig. 1 and looking downward but the section is not exactly a regular section on that line.

Fig. 5 is a perspective view of the elastic 25 stop piece.

The drawing shows the invention applied to a Remington No. 12 typewriter which being well known is shown in the drawings only enough to illustrate the application of my improvement thereto.

30 The main frame of the machine comprises a top plate 5 mounted on corner posts 6 and having projecting upward therefrom posts or lugs 7 on which are mounted stationary rails 8 which rails by means of bearing rollers 10 support the transverse bars 11 of the carriage truck.

35 The margin stop mechanism to which my invention is shown applied is of the kind commonly used in the Remington No. 12 machine, and it is substantially of the construction shown and described in the patent to George A. Seib, dated July 6, 1920, No. 1,345,894. On the front bar 11 of the carriage truck there is mounted a bar 12 which is toothed along its front edge to cooperate with two margin stops, namely, a left-hand stop 13 and a right-hand stop 14. Each of these stops comprises a block of metal mounted in a well known way and adjustable by means of a finger piece 15 along the length of the carriage bar to letter space positions determined by pointers 16 cooperating with a scale 17. The stop pieces have forwardly project-

ing portions having abrupt stop surfaces 18 55 adapted to strike against the relatively stationary stop, the latter consisting of a block 20 supported at the middle of the machine on the stationary rail 8. This block 20 is fast on a sliding rod 21 adapted to slide a short distance right and left in a barrel 22 secured by screws 23 to the front face of the rail 8.

The block 20 has an integral lug 24 projecting from its rear face into a cut-out 25 65 in the front face of the bar 8. As ordinarily constructed in the Remington machine this lug 24 is of less width in a right and left-hand direction than the cut-out 25 so as to allow to the block 20 a limited motion in 70 a right and left-hand direction, its motion being arrested in each direction by the lug 24 striking a wall of the cut-out 25.

The block 20 has projecting downward therefrom an arm 26 which engages in a 75 notch in a sliding device 27 mounted underneath the rail 8 by means including a screw 28. At its left end the device 27 is bent down and engages in a notch in the upright arm of a bell crank 30 whose horizontal arm is 80 pivoted to a vertical link 31 which goes down into the base of the machine where it controls a key lock. A spring acting on this train of mechanism holds the block 20 normally in its right-hand position, but it can be moved 85 a limited distance to the left by the margin stop 14 to work the key lock at the end of a line.

90 My improvement includes a resilient stop or cushioning device for the block 20, said stop in the present instance, and preferably, consisting of a C-shaped piece of sheet metal 32 secured to the front of the bar or rail 8. As shown in Figs. 2 and 4 said bar 8 is made on its front face with a shallow slot 95 which just fits the left-hand branch or arm of the piece 32, which arm is further secured in position by a pin 33 passing through the piece 32 and into the rail 8. The piece 32 extends downward from the pin 33 and 100 curves approximately semi-circularly rightward and upward, its right-hand end lying in a suitable cut-out in the front face of the bar 8. This cut-out terminates at 34 in an abrupt shoulder and the parts are so proportioned as that the right-hand edge of the elastic stop member 32 stands slightly to the 105 left of the shoulder 34. The piece 32 is made

with an ear or finger 35 which lies on the rail 8 which may be flattened off to form a ledge for the purpose.

The right-hand branch of the C-shaped member 32 has projecting leftward therefrom a lug 36, the left-hand edge of which stands in the position at which the right-hand edge of the block 20 should normally stand. The cut-out 25 in the rail 8 is widened toward the right slightly so that its right-hand wall is a little to the right of the left-hand edge of the lug 36. The whole construction is such that when the carriage is drawn to the right and the contact surface 18 of the margin stop 13 strikes the block 20 the shock of arrest springs the stop piece 32, allowing the lug 36 to move slightly toward the right. The distance toward the right to which this part can spring is limited either by the situation of the shoulder 34 with respect to the piece 32 or by the situation of the right-hand wall of the cut-out 25 with relation to the left-hand edge of the lug 36. Obviously the piece 32 cannot spring beyond the shoulder 34 and obviously also the lug 24 on the piece 20 cannot move beyond the right-hand wall of the cut-out 25.

As is well known the carriage of the Remington machine is arrested at the front of the machine and the escapement mechanism is at the back of the machine. If the stop piece 32 had more than a certain amount of springing action on the arrest of the carriage it would result in the carriage overthrowing beyond its normal position to a sufficient extent to cause the escapement ratchet wheel to be caught one space too far. This would be produced by a blow due to the sudden arrest of the carriage and the result of it would be that the parts would be under tension and the carriage would be one letter space further to the right than it should be. In making an elastic stop of the sort here shown and described it is therefore essential that the extent to which the stop can spring be rather strictly and accurately limited. In making the machine therefore the parts are so proportioned as to give a definite and predetermined extent of freedom of the right-hand branch of the member 32 to spring. In the specific instance described, the shoulder 34 and the right-hand wall of the cut-out 25 are so proportioned as to allow the stop piece 32 to spring not more than ten or fifteen one-thousandths of an inch. If the carriage be drawn back violently enough so that the piece 32 would spring further than this predetermined amount, it is positively arrested. The piece 32 is cut into the C-shape shown, so that the stress on it, when it arrests the carriage, comes edgewise

of it, thus making it stiff. The stiffness of the spring action of the piece 32 can be regulated by the design of said piece, as will be readily understood. It is essential that the piece be stiff enough so that the ordinary return motion of the carriage will spring it a shade short of its maximum amount and no more. It may therefore be called a stiff elastic piece.

On account of the fact as above explained that it is not permissible to allow more than a small amount of spring to the elastic stop, it is obvious that this stop will not entirely prevent all noise due to the return of the carriage. If the carriage is drawn back very rapidly it will be arrested positively as above explained and a noise will be made correspondingly. But under the ordinary return motion as imparted to these carriages by hand by an ordinary operator the arrest of the carriage is considerably softened and the noise of arrest is diminished and is changed in quality from a sharp and penetrating metallic sound to something more in the nature of a dull thud.

One of the principal advantages of my cushioning means, resides in its extreme simplicity and the ease with which it can be applied to the machine.

What I claim as new and desire to secure by Letters Patent, is:—

1. The combination with a carriage and co-operating stops by which it is arrested, of a cushioning device associated with one of said stops and consisting of a stiff elastic C-shaped piece of flat metal held at one end and yielding slightly at the other.

2. The combination with a carriage and co-operating stops by which it is arrested, one of said stops consisting of a sliding device, of a stiff elastic C-shaped piece of metal held at one end and engaged at the other end between its two branches by said sliding stop device and yielding slightly to the shock of arrest of the carriage.

3. The combination with a carriage, a margin stop 13 carried by said carriage, and a stop device 20 slidably mounted on the stationary framework and having a lug 24, of a cushioning device for said stop 20 comprising a C-shaped piece of flat metal rigidly held at one end and engaged at the other end between its branches by said lug and yielding slightly to the shock of arrest of the carriage.

Signed at the borough of Manhattan, city of New York, in the county of New York and State of New York, this 2nd day of December, A. D. 1927.

EDWIN E. BARNEY.
